BORING BAR

William S. Hutchinson, Port Jefferson, N. Y.

Application April 11, 1949, Serial No. 86,759

2 Claims. (Cl. 77—58)

1

The invention relates to a boring bar having a bit holder, and has for its object to provide such a holder to enable the time of the operator to be saved in connection with the grinding of the bit.

In this improvement the front and side rakes of the bit are pre-determined by a channel in the boring bar and it is only necessary to grind the bit to provide the clearances. Inclinations of the channel to the longitudinal axis of the holder determine the most effective rakes, both front and side. A full length of tool bit may be used, thus enabling the use of a standard tool bit. As the rakes are determined, by reason of the improvement, by the channel in the boring bar itself, the grinding of the front and side rakes is dispensed with. Depending on the different metals to be worked, the tool bit can be ground for clearance to any shape in respect to such already determined rakes without changing said rakes. Thus only clearance grinding is necessary, which any mechanic can do, a skilled or expert grinder not being required as is the case for the grinding of rakes. The boring bar itself is usually horizontal. The tool bit slants downwardly away from the work, and provides the front rake, and the side rake is inclined from left to right (looking at the work) and also drops the chips away from the cut.

The invention then consists of a boring bar having a channel with a contour substantially that of the exterior contour of a standard bit, said channel having its longitudinal axis at two inclinations to the longitudinal axis of the holder, with sidewalls of the channel askew to the longitudinal axis of the holder, to provide the desired front and side rakes of the bit, without special grinding of the rakes, it being only required to grind the cutting end of the bit, to provide the necessary clearance of the bit to the work.

The invention will be more fully described hereinafter, embodiments thereof shown in the drawings, and the invention will be finally pointed out in the claims.

In the accompanying drawings,

Fig. 1 is a perspective view of the improved boring bar with the bit therein;

Fig. 2 is a vertical section taken on line 2—2 of Fig. 1, the bit being omitted;

Fig. 3 is a horizontal section taken on line 3—3 of Fig. 2;

Fig. 4 is a vertical section taken on line 4—4 of Fig. 2;

Fig. 5 is a diagram of Fig. 3;

Fig. 6 is a diagram of Fig. 2;

2

Fig. 7 is a top view of the bit shown in Fig. 1;

Fig. 8 is a front view of the same;

Fig. 9 is a top view of another form of the bit; and

Fig. 10 is a front view of the same.

Similar characters of reference indicate corresponding parts throughout the various views.

Referring to the drawings, the boring bar 10 has a plane front surface 11 adapted to be brought near the work. A channel 12 extends diagonally across the boring bar 10 having a cross-sectional area slightly larger than the cross-sectional area of the bit 15 to enable the bit to be inserted therein and to be moved therein. The longitudinal axis of the channel is inclined in two directions to the axis of the holder 10, preferably about 15 to 20° to a vertical plane 20 (Fig. 5), and about 8 to 20° to a horizontal plane 22. The channel 12 has its flat sides 12a, 12b, 12c, and 12d (Fig. 4), angularly disposed both to the horizontal and perpendicular (Fig. 4). The channel 12 in the boring bar is made square for standard tool bits and is slanted from front down toward the back as in Fig. 5, where the direction 21 of the bit is shown in respect to the vertical plane 20, and tilted from left to right as in Fig. 6, where the direction of the bit 23 is shown in respect to the horizontal plane 22, thereby predetermining both front rake and side rake of tool bit in the boring bar itself. The bit 15 is held in the channel 12 by Allen screws, three (13) on the top for holding tool bit down, and one (13a) at the side of the holder 10, for sidewise holding. The bit 15 projects slightly out of the channel 12 beyond the face 11 to enable the work (not shown) to be bored or machined.

Various cutting shapes of bits may be used. Two forms are shown; one in Figs. 7 and 8, and one in Figs. 9 and 10. In Figs. 7 and 8, an angular edge 16 makes an acute angle with an angular edge 17, and the edges 16 and 17 are formed by angular plane surfaces extending from edge 16 to edge 18, and from edge 17 to edge 19. The most forward point 15a is the cutting point. In Figs. 9 and 10, the bit 15 has a different cutting point 35. Edges 30, 31, 32 and 33, form the forward cutting point 35. The edge 32 is set back, as also the edge 33. These examples are shown to illustrate the clearance grindings. It is noted that the top surfaces of these bits were not especially ground to form rakes.

Among the advantages of the improved boring bar are: made to use standard tool bits full length. Made to hold tool bit at any predetermined side rake and front rake. Made to hold

tool bit in approximate center of tool post center. Made to be held in tool post on approximate straight line with cut. Made to eliminate almost all side torque thereby eliminating almost all chatter. Made to take heavier cuts without side spring thereby cutting truer to set. A heavy cut can be taken and tool and carriage drawn back and in again, and it will not have a second cut as most conventional bars do. With front and side rake already on tool bit it is easier and quicker to grind without weakening tool bit in so doing. The cutting surface of top of tool bit does not ever have to be ground. Only clearance and front shape need be ground. The boring bar permits more strength and rigidity for any given diameter hole to be bored. The boring bar can, of course, be made in different sizes accommodating all standard tool bits. The tool bit itself is held by Allen set screws both up and down and sideways. The preferred boring bar has its front end with corners rounded off as shown in the front end by shading in Fig. 1. The tapered portion extends from the plane front surface 11 and terminates before the known holding portion of the boring bar. The cutting surface of the tool bit projects out of the front side 11 of the front end of boring bar 10. This boring bar and tool bit combination eliminates most of the skill needed to grind tool bits as required in all conventional boring bars.

The front end of the boring bar is tapered, with the taper extending from the front surface 11 to a part of the boring bar. The boring bar at its rear end is square or rectangular to be gripped in a standard tool post, as known.

Reference is made to a companion application filed subsequent to this application but on even date herewith, under Serial No. 86,760 on April 11, 1949.

I wish it to be understood that I do not desire to be limited to the exact details of construction shown and described, for obvious modifications will occur to a person skilled in the art.

I claim:

- 5 1. In a boring bar having a shank with left and right sides in the direction of its longitudinal axis towards its front, and with a front face perpendicular to said axis, and having a channel with an internal contour of the transverse exterior contour of a standard tool bit with an axis, having an inclination in respect to a vertical plane from said front face towards the rear of the shank, the combination of said channel axis extending from the front upper left side to the lower right side of the shank, and the walls of said channel being inclined to the vertical and to the horizontal with the highest corner adjacent the 10 left side of the shank and with the left corner of the channel contiguous to said left side of the shank, whereby a tool bit having a front and side rake inserted in said channel extends laterally out of the left side of the shank and the 15 top surface of the protruding end of the tool bit acts to slide the chips both ways away from the cutting edge, no other grinding of the tool bit, other than for clearance, being necessary.
- 20 2. The structure of claim 1, in which the inclination of the channel axis to a horizontal plane is 8 to 20°, and the inclination of said axis to a vertical plane is 15 to 20°.

WM. S. HUTCHINSON.
